UNITED STATES PATENT OFFICE.

ROLLA W. HESS, OF ST. LOUIS, MISSOURI.

DESIGN FOR A SPOON.

SPECIFICATION forming part of Design No. 20,682, dated April 21, 1891.

Application filed March 14, 1891. Serial No. 385,131. Term of patent 7 years.

To all whom it may concern:

Be it known that I, ROLLA W. HESS, of St. Louis, Missouri, have invented and produced a new and original Design for Spoons and

- 5 Forks, of which the following is a specification, reference being had to the accompanying drawing, forming part thereof, and which is a face view of a spoon having the newly-designed handle.
- 10 The invention relates more especially to the stem of the spoon; and the leading feature of the design consists in the representation of the veiled face a of the personage popularly known as the "Veiled Prophet," of St. Louis.
